UNITED STATES PATENT OFFICE.

CHARLES H. BOWERS, OF DEFIANCE, OHIO, ASSIGNOR OF ONE-HALF TO
THOMAS J. CONLEY, OF SAME PLACE.

DESIGN FOR A WAGON-STAKE.

SPECIFICATION forming part of Design No. 15,313, dated August 26, 1884.

Application filed May 24, 1884. Term of patent 14 years.

To all whom it may concern:

Be it known that I, CHARLES H. BOWERS, of Defiance, in the county of Defiance and State of Ohio, have invented a new and original Design for a Wagon-Stake, of which the following is a full, clear, and exact description.

My design for a wagon-stake consists in a novel configuration of the base or socket portion of the stake and of the upright or standard thereon.

Reference is to be had to the accompanying drawings, forming part of this specification, in which similar letters of reference indicate corresponding parts in both the figures.

15 Figure 1 represents a side view of a wagon-stake embodying my design, and Fig. 2 an outer end elevation of the same.

A designates the base or socket portion of the stake, which is in the form of a band of 20 rounded configuration at its outer end, *a*, and having its lower edge made to present a series of irregular corrugations composed of curved and straight lines commencing with a front or outer end convex portion or margin, *b*, merging 25 on each side of the band-like base into a concave line, *c*, that terminates in a convex line, *d*, from which the marginal configuration is continued by a straight line, *e*, sloping upward and backward, and terminating in or joining 30 a convex line or inner end and lower marginal configuration, *f*.

B designates the standard or upright of the stake, and the back *g* of which presents a flat straight face configuration, tapering upward and rounded at its top *h*, but spreading laterally by graceful concave lines *i* at its lower end, where it joins rounded flat projections *k* on the base A. Centrally up the outer face of this back *g* of the standard B is a 40 rib, *l*, having parallel sides, but of irregular tapering width in an upward direction, and the side configuration of which presents an upper convex line, *m*, outwardly-inclining straight lines *n*, joined above by a marginal line, *r*, of ogee shape, and terminating below by a convex line, *s*, in a foot-piece that presents an upper downwardly and outwardly inclining margin, *u*.

Having thus described my design, I claim as new and desire to secure by Letters Patent— 50

1. The within-described design for a wagon-stake, which consists in a base, A, of band-like form, having a rounded outer end configuration, *a*, and an irregularly-corrugated marginal configuration for its lower edge, composed of a 55 convexity, *b*, merging on each side into a concavity, *c*, terminating in a convexity, *d*, whence said marginal configuration is continued by an upward and backward sloping line, *e*, to and terminating in a convexity, *f*, as shown. 60

2. The within-described design for a wagon-stake, which consists of a standard, B, having a back, *g*, the facial configuration of which presents an upwardly-tapering form ornamented down its center by a rib, *l*, of irregular tapering width, and the outer margin of which is composed of an upward convexity, *m*, and outwardly-inclining straight lines *n*, joined above by an ogee-shaped line, *r*, and terminating below by a convexity, *s*, in a downwardly 65 and outwardly inclining margin, *u*, as shown. 70

3. The within-described design for a wagon-stake, which consists in part of a base, A, of band-like form, having a rounded outer end configuration, *a*, and an irregularly-corrugated 75 marginal configuration for its lower edge, composed of a convexity, *b*, merging on each side into a concavity, *c*, terminating in a convexity, *d*, whence it is continued by a sloping line, *e*, to and terminating in a convexity, *f*, as shown, 80 and in part of a standard, B, having a back, *g*, the facial configuration of which presents an upwardly-tapering form, ornamented down its center by a rib, *l*, of irregular tapering width, and the outer margin of which is composed of 85 an upper convexity, *m*, and outwardly-inclining straight lines *n*, with an ogee-shaped line connection, *r*, above and connected below by a convexity, *s*, with an outwardly-inclining margin, *u*, as shown.

CHARLES H. BOWERS.
